UNITED STATES PATENT OFFICE.

HENRY ZIEGLER, OF NEW YORK, N. Y.

MUSIC-RACK ATTACHMENT FOR UPRIGHT PIANOS.

SPECIFICATION forming part of Letters Patent No. 408,868, dated August 13, 1889.

Application filed March 8, 1889. Serial No. 302,529. (No model.)

To all whom it may concern:

Be it known that I, HENRY ZIEGLER, of the city, county, and State of New York, a citizen of the United States, have invented certain new and useful Improvements in Music-Rack Attachments to Upright Pianos, of which the following is a specification.

This invention relates to an improved music-rack attachment for upright pianos, which rack can be readily lowered into inclined position over the lid of the piano and returned into its normal position into the front opening of the case; and the invention consists of the case of an upright piano which is provided in its front wall with an opening which is closed by a rack that is hinged by curved brackets to a vertically-sliding panel that is guided in ways at the upper rear part of the front wall of the case. The hinged rack is further connected with the front wall of the case by a hinged extensible strap which supports it in lowered inclined position. The rack is retained by a suitable locking device in the opening of the case when returned into normal position in the same, and released from said locking device by simply lifting the hinged and sliding panels so that the hinged rack clears the locking device, and can then be lowered and set into inclined position over the opened lid of the piano. The sliding panel follows the hinged rack in its downward motion, and serves to fill up the open space above the hinged panel.

In the accompanying drawings, Figure 1 represents a perspective view of an upright piano with my improved music-rack attachment shown in lowered position and ready for use. Figs. 2 and 3 are vertical transverse sections of the front wall of an upright-piano case, showing the music-rack respectively in normally closed and in lowered position. Fig. 4 is a rear elevation of the front wall with the music-rack attachment in closed position and partly in section through one of the guide-ways of the upper sliding panel of the rack; and Figs. 5 and 6 are a detail rear elevation and a vertical transverse section of the strap-connection between the front wall of the piano and the hinged rack, drawn on a larger scale. 50 Similar letters of reference indicate corresponding parts.

Referring to the drawings, A represents the front wall of an upright-piano case, which wall is provided at its center part with an oblong opening *a* of suitable size. This opening 55 is closed by a rack B, which is hinged by means of curved brackets *b* to the lower part of a sliding panel C, which is guided in grooved ways C', located at the upper rear part of the front wall A, as shown clearly in Figs. 2, 3, 60 and 4. The ways C' are provided at their lower ends with stops *d* and at their upper ends with springs *d'*, which press on the top edge of the sliding panel C. The lower edge of the hinged rack B is locked by 65 a hook *e* to an inclined projecting hook *e'*, that is attached to the lower edge of the opening *a* in the front wall A. The hinged rack B is further connected by an extensible hinged strap F with the lower part of the front wall 70 A of the opening *a*, as shown clearly in Figs. 2 and 3, said hinged strap being formed of two parts *f'f*', of which one is hinged to the rack B, while the other is hinged to the front wall A, and which are connected by headed studs *f*², 75 that are attached to one strap and passed through slots *f*³ of the other strap, as shown clearly in Figs. 5 and 6. A spring *g* is attached to the front wall below the lower edge of the opening *a*, and arranged so as to press 80 on the lower part of the rack B, as shown clearly in Figs. 4 and 6. The rack B is of somewhat smaller height than the height of the opening *a*, and provided with an overlapping molding *m* at its outer edge, that extends 85 over the edges of the opening *a*. The difference in height between the rack B and the opening *a* is necessary for the purpose of permitting the lifting of the rack B in the opening *a* to such an extent that the locking-hook 90 *e* at the lower part of the panel can clear the hook *e'* at the lower edge of the opening *a*. This lifting of the rack B also produces the lifting of the sliding panel C against the tension of the springs *d'*, which latter press the 95 panel C and rack B in downward direction as soon as the locking-hooks are released from each other. Simultaneously the spring *g* moves the rack B in a forward direction, so that it clears the lower edge of the opening 100 *a* and moves with the sliding panel C in a downward direction until the motion of the

sliding panel is arrested by the stops *d*, and the rack *B* retained in its inclined lowermost position by the hinged strap *F*, as shown in Fig. 3. The small degree of extension of the hinged strap *F* is required for permitting the lifting of the rack *B* in the opening *a* preliminary to unlocking or locking the same. Without the extensibility of the hinged strap the locking or unlocking operation of the hinged rack *B* could not be accomplished.

For operating my improved music-rack attachment for upright pianos the front rack *B* is taken hold of at the lower molding and slightly lifted by upward pressure on the same until the locking device is released and the rack *B* moved in a forward direction by the spring *g*. The hinged rack *B* and the sliding panel *C* are then permitted to move in a downward direction until the sliding panel is arrested by the stops *d*. The rack *B* assumes, then, an inclined position and extends over the open lid *L*, so as to support the music-sheets on the hinged ledge *l* of the lid in connection with the inclined rack *B*, as customary in music-racks for upright-piano cases. When the hinged rack *B* is in its lower position, the open space above the rack at the part of the opening *a* is closed by the sliding panel *C*, which is preferably provided with suitable openings. For returning the rack *B* into its normally-closed position in the opening of the front wall *A* the rack is moved in an upward direction, which motion returns the sliding panel *C* into its raised position, so as to lift the springs *d'* and permit the locking-hooks to interlock with each other, while simultaneously the spring *g* at the lower part of the front wall *A* is pressed back by the rack *B*.

My improved music-rack attachment has the following advantages: First, there are no parts visible from the outside which disclose that the front panel can be opened; secondly, it permits the sounds to pass through the opening in the front wall to the outside; thirdly, it closes the space above the hinged rack when the same is lowered by an ornamental panel, which can be moved up and down without interfering with the string-frame of the piano located immediately back of the same, and, fourthly, the hinged rack is supported in its inclined and lowered position without forming contact with the lid, so as not to scratch or otherwise injure the edge of the same.

Having thus described my invention, I claim as new and desire to secure by Letters Patent—

1. The combination, with the front wall of an upright-piano case having an opening, of a sliding panel guided at the upper rear part 60 of the front wall and of a main panel or rack fitting into said opening and hinged to said sliding panel, substantially as set forth.

2. The combination, with the front wall of an upright-piano case, said front wall having 65 an oblong opening, of a sliding panel guided in ways at the upper rear part of the front wall, a rack hinged to said sliding panel and fitting into said opening, and an extensible hinged strap-connection between the front 70 wall and the hinged rack, substantially as set forth.

3. The combination, with the front wall of an upright-piano case, said front wall having 75 an opening, of a sliding panel guided in ways at the upper rear part of the front wall, stops at the lower end of said guideways for arresting said sliding panel, and a rack fitting into the opening of the front wall and hinged to the lower part of the sliding panel, substantially 80 as set forth.

4. The combination, with the front wall of an upright-piano case, said front wall having an opening, of a sliding panel guided in ways at the upper rear part of said front wall, stops 85 at the lower ends of said guideways, springs at the upper ends of said guideways, a rack hinged by curved brackets to the lower part of the sliding panel, a locking device connecting the lower end of the rack with the lower edge of the opening, and a spring attached to the front wall and adapted to press the rack forward when the locking device is released, substantially as set forth.

5. The combination, with the front wall of 95 an upright-piano case, said front wall having a central opening, of guideways at the upper rear part of said front wall, a sliding panel guided in said ways, a rack hinged to the lower part of said sliding panel and made 100 somewhat less in height than the opening in the front wall, and a locking device at the lower part of the rack and opening of the front wall, said locking device being locked or unlocked by lifting the rack in the opening of 105 the front wall, substantially as set forth.

In testimony that I claim the foregoing as my invention I have signed my name in presence of two subscribing witnesses.

HENRY ZIEGLER.
